STEAM IRON

Robert J. Scott, Blue Springs, Mo., assignor to
 John C. Hockery, Kansas City, Mo., as trustee
 for Henry J. Talge and Foster L. Talge

Application December 19, 1951, Serial No. 262,360

9 Claims. (Cl. 38—77)

1

The present invention relates in general to flat irons for pressing fabrics, and it deals more particularly with an improved construction in electric steam-generating irons.

Broadly speaking, it is the object of the invention to provide a steam iron of the type having a self-contained boiler or water storage reservoir and which may be used either with or without water in the boiler depending upon whether the operator desires to do "steam ironing" or "dry ironing."

In this connection, an important object resides in the provision in a steam iron of the foregoing type of means for emptying the water reservoir or boiler quickly, easily and conveniently while the iron is hot in order to convert the unit to a "dry" iron with a minimum of trouble and delay; or in order to clear the boiler of water preparatory to storing the iron away after a particular steam pressing job has been completed.

A feature of the invention lies in providing valve means for closing the boiler's steam discharge passageway at will and, when this is done, in utilizing the steam pressure in the boiler to drive the water out through an auxiliary passageway. According to another feature, the water is discharged from the boiler under the foregoing circumstances through the same outlet as is used in discharging steam from the boiler in the course of the normal steam ironing operation.

Another object is to provide a valve and passageway construction of the character indicated which is readily accessible for service purposes for replacement of parts and for cleaning.

Other and further objects of the invention, together with additional features of novelty by which the objects are achieved, will appear in the course of the following description.

In the accompanying drawings which form a part of the specification and are to be read in conjunction therewith, and in which like reference numerals are employed to indicate like parts of the various views:

Fig. 1 is a side elevational view of a steam iron embodying my invention, parts having been broken away for purposes of illustration.

Fig. 2 is an enlarged cross-sectional detail of the valve and conduit construction employed in my iron, and

Fig. 3 is a fragmentary cross section taken along the line 3—3 of Fig. 1 in the direction of the arrows.

The steam iron shown in the drawings is of the general type disclosed in Patent 2,475,572, issued to Edward P. Schreyer on July 5, 1949. It

comprises a sole plate 10 with a boiler shell 12 mounted on the upper surface thereof; an electrical resistance element 14 embedded in the sole plate is adapted to heat the latter and also the water 16 contained in the boiler.

Hinged to the upper side of the boiler at 18 is a cover or shield plate 20, and this has a handle 22 secured to it by screws. The forward end of the shield plate and handle assembly thus may swing up and down about the hinge 18. However, near its forward end the shield plate carries a latching member 24 adapted to be engaged with a catch 26 disposed on the upper side of the boiler in order to hold said plate and handle assembly down. The latch may be engaged or disengaged at will by manipulation of the latch control knob 28. This latching mechanism, as well as the structure and function of the shield plate, are explained fully in the aforementioned Schreyer patent so need not be dealt with in detail here.

As also described in the Schreyer patent, the upper wall of the boiler is provided with a funnel-like filler opening 30 to which access may be had (for filling the boiler with water) when the shield plate is unlatched and swung up to its raised position. The lower rim of the filler opening is considerably below the top of the boiler, which prevents the water from rising above a predetermined level in the boiler and insures that there is always an air or steam space above the surface of the water. When the shield plate is swung back down and latched, a spring-biased closure 32 carried on the underside of the plate seats against and seals the filler opening.

In the forward portion of the boiler I provide a generally horizontal baffle 34 whose entire lateral margin is in contact with the inside wall of the boiler shell. Preferably, the medial portion of the baffle is concavo-convex and/or the baffle is formed with corrugations as shown to increase its rigidity.

A stand pipe or steam discharge tube 36 extends through the baffle approximately centrally thereof and has its lower end welded or brazed in an aperture in the bottom 12a of the boiler. The tube may also be welded or brazed to the baffle where it passes therethrough in order to give the latter central support, but in the interest of manufacturing economy and simplicity, I prefer to obtain this support by means of a coiled compression spring 37 which encircles the tube and presses upwardly on the baffle. Joining tube 36 near its upper extremity is an auxiliary tube 38 that extends diagonally downward through the baffle and has its lowermost end against the bot-

tom of the boiler in the forwardmost portion thereof close to the juncture of the side walls 12b (see Fig. 3); the purpose of this will be made clear presently.

Tube 36 communicates at its lower end with a chamber 40 in the sole plate, the latter being covered by a flat plate 42. Around this cover plate is a marginal opening 40a through which steam can escape from the chamber 40 onto the fabric being ironed. That is to say, in the course of the normal use of my unit as a steam iron, the steam generated within the boiler 12 passes upwardly around the baffle 34 into the steam space 44; entering the upper end of tube 36, it then flows downwardly through the tube into chamber 40 and escapes through the outlet port around the margin of plate 42. (The latter plate, it will be noted, also serves to conceal the screw 46 employed to anchor the forward end of the boiler to the sole plate.)

The assembly at the upper end of steam tube 36 comprises an externally threaded bushing 48 received in an aperture in the top wall of the boiler and having a flange 48a that is welded or brazed to the boiler as may best be seen in Fig. 2. A vertically elongated cap 50 is screwed to this bushing, the two elements together forming a dome which extends upwardly from the boiler so that its upper end is received in a cavity 52 in the forward post of handle 22. The top of the cap is apertured as shown at 50a.

Between the upper end of bushing 48 and an internal shoulder 50b in the cap is a centering washer or guide 54 which slidably supports the valve stem 56. The upper end of the latter is enlarged as shown at 56a and a coiled compression spring 58 between the enlargement and the centering washer serves normally to maintain the valve stem in raised position as shown. The lower end of the stem is of reduced diameter and has a tapered valve member 60 screwed thereto, a spacing washer 62 and a sealing disk 64 being clamped between the valve member and the shoulder 56b on the stem. The valve member 60 is, of course, centered above the open upper end of steam tube 36. Disk 64 is formed of gasket material that is unaffected by the moisture and high temperature of the steam to which it is subjected; and by its sealing engagement with the bore 48b of bushing 48, it prevents escape of steam into the cap 50.

In the upper forward portion of the handle 22 of my iron, there is a socket 66 which loosely receives thumb button 68. A plunger shaft 70 extends downwardly from the button, this being aligned with the valve stem 56 and normally having its lower end resting lightly on the top of the valve stem which is of course exposed through the aperture 50a in the cap 50. A snap-ring 72 disposed in a suitable annular groove on the plunger shaft prevents the latter from moving upwardly beyond the position shown.

By way of describing the operation of the foregoing arrangement, let it be assumed that my device is in use as a steam iron; that is to say, steam generated as the result of the boiling of the water 16 passes through the steam space 44 into the upper end of tube 36, then flows downwardly through the tube into the chamber 40 and escapes through the outlets 40a onto the fabric being ironed. If this mode of operation is continued sufficiently long, the water 16 will of course become exhausted through the conversion of all of it into steam; and the iron then may be used as a conventional "dry" iron or alternatively

the boiler may be refilled for continued use of the unit as a steam iron.

However, it often happens that while the boiler still contains a substantial amount of water, the operator desires to press some particular garment without discharging steam into the fabric, and it becomes very desirable in such event to be able to effect the conversion to dry-iron operation without the delay that would be involved in "boiling away" all of the remaining water in the usual fashion. Again, in the event water remains in the boiler when a particular pressing job has been completed, it is wasteful of time and electricity if it is necessary to allow the iron to continue heating for a prolonged interval in order to clear the boiler of water before the iron is stored away.

According to my invention, if it is desired at any time to discontinue generating steam and empty the water remaining in the boiler, it is only necessary for the operator to press on the thumb button 68 for a brief interval while the sole plate continues to heat. This obviously moves valve 60 downwardly so that it seats in and closes the upper end of the steam discharge tube 36. The pressure of the steam acting downwardly on the surface of the water now causes the water to flow upwardly in tube 38, then downwardly in tube 36 so that it enters chamber 40 and is blown out of the marginal opening 40a by the steam.

The discharge of the water takes place rapidly and can be facilitated by tipping the forward end of the iron slightly downward near the end of the operation. This places the open lower end of tube 38 at what becomes the lowest point in the boiler, and since the last remaining water will drain to this point and enter the tube, the boiler is made virtually dry in a very brief interval.

During the foregoing emptying operation, baffle 34 also helps, in the event the iron is tipped forward rather abruptly, to keep the water in the correct region of the boiler to enter tube 38. During the conventional steam ironing operation, of course, the baffle prevents the water from splashing into the open upper end of tube 36 due to the motion of the iron.

When the thumb pressure is removed from button 68 after an emptying operation, it will be evident that spring 58 restores the valve 60 to the position shown, opening the upper end of tube 36. It will also be clear that whenever the handle and shield plate assembly is unlatched as described hereinbefore and swung up about hinge 18 to give access to opening 30 for the purpose of filling the boiler with water, the thumb button and plunger 70 move upwardly with the handle; however, on bringing the latter back to the position illustrated and latching it down, the plunger is brought back into juxtaposition with the valve stem 56 so that the emptying operation may thereafter be carried out as explained, without any further adjustment or presetting of the parts.

When the handle and shield plate assembly is swung up, access is had not only to the filler opening 30 but also to the valve assembly which controls the water-emptying operation. That is to say, it is only necessary now to unscrew cap 50 in order to disassemble the valve mechanism for replacement of the sealing disk 64 or other servicing. Also, when the valve parts are removed, access is had to the upper end of tube 36, which facilitates cleaning the latter and permits

removal of any foreign matter that may have become lodged therein.

While I have shown the water discharge tube 38 as being diagonal and having its lower end close to the forward juncture of side walls 12b to facilitate complete removal of the water, it will be evident to those versed in the art that this is not absolutely essential. It is important, however, that the lower end of the tube be close to the bottom of the boiler and that the upper end communicate with the steam discharge tube 36 at a point somewhat above the surface of the water; otherwise, the water would overflow into tube 26 even when valve 60 is open, causing globular water to be discharged along with the steam in the course of the normal steam-ironing operation.

Inasmuch as various possible modifications of the invention thus may be made without departing from the scope thereof, it is to be understood that all matter herein set forth or shown in the accompanying drawing is to be interpreted as illustrative and not in a limiting sense.

From the foregoing, it will be seen that this invention is one well adapted to attain all of the ends and objects hereinbefore set forth, together with other advantages which are obvious and which are inherent to the apparatus.

It will be understood that certain features and subcombinations are of utility and may be employed without reference to other features and subcombinations. This is contemplated by and is within the scope of the appended claims.

I claim:

1. In a steam iron, a sole plate having means for heating same, a liquid-receiving boiler on the sole plate, said boiler having an enclosed steam space above a water space, a duct having an upper opening located in said steam space and having its lower end extending through the sole plate to discharge steam from said steam space onto material being ironed, said duct having a valve at said upper opening, means normally holding said valve open, means for closing said valve, whereby said opening may be closed, a second duct in open communication at one end with said first duct below said upper opening and valve and having its other end extending into said liquid space in the boiler, whereby when said valve is closed the flow of steam from said steam space into said duct is cut off and the steam pressure in the steam space is caused to force water from the water space up said second duct and thence down the first duct.

2. A steam iron as in claim 1 wherein the submerged end of said second duct is open in the liquid space in said boiler at a point near the front end of the bottom of the boiler.

3. In a steam iron, a sole plate having a steam outlet port in its lower surface, a liquid-receiving boiler mounted on the upper surface of said sole plate, said boiler having an enclosed steam space above a water space, a duct having its lower end located in the liquid space in the boiler and its upper end connected to said outlet port, the portion of said duct intermediate said two ends extending through said steam space and containing an opening through which steam from said space normally enters the duct, and valve means associated with said opening for closing said duct to the steam space, thereby to cause the steam pressure acting on the surface of the liquid to force the liquid into said duct through said one end and discharge same through said outlet.

4. A steam iron as in claim 3 wherein the sub-

merged end of said duct is open to the liquid in the boiler at a point near the front end of the bottom of the boiler.

5. In a steam iron, a sole plate having a steam outlet port in its lower surface, a water reservoir mounted on the upper surface of the sole plate, said reservoir having a water space and an enclosed steam space above said water space, a steam discharge duct communicating at its lower end with said outlet port and communicating at its upper end with said steam space, valve means associated with the upper end of the duct for closing same off from said steam space, and means providing a passageway from said water space into said duct below said valve means whereby water can enter said duct from said water space when the upper end of said duct is closed off from the steam space, said means comprising an auxiliary duct having one end located in said water space at a point near the bottom of the reservoir, the other end of said auxiliary duct being in open communication with said first duct at a point below said valve means.

6. In a steam iron, a sole plate having a steam outlet port in its lower surface, a water reservoir mounted on the upper surface of the sole plate, said reservoir having an enclosed steam space above the surface of a water space, a stand pipe communicating at its lower end with said outlet port and extending upwardly therefrom through the water space in the reservoir, the upper end of the stand pipe being above said water space, a valve member above the stand pipe and in alignment therewith, spring means urging said valve member upwardly so it normally is spaced above the upper end of the stand pipe, manually operable means for moving the valve member downwardly against the force of said spring to close the upper end of the stand pipe off from said steam space, and means providing a passageway from said water space into said stand pipe, said means comprising a duct having one end located in the space in the reservoir at a point near the bottom of the reservoir, the other end of said duct being in open communication with said stand pipe at a point below the upper end of said stand pipe and valve member.

7. In a steam iron, a sole plate having a steam outlet port in its lower surface, a water reservoir mounted on the upper surface of the sole plate, said reservoir having an enclosed steam space above a water space, a stand pipe communicating at its lower end with said outlet port and extending upwardly therefrom through said water space, the upper end of said stand pipe being above the water space, a dome in the top of the reservoir over the upper end of the stand pipe, a valve element supported in said dome for vertical movement, spring means urging said valve element upwardly so it normally is spaced above the upper end of the stand pipe, the top of the dome containing an aperture, means including an operating member having operative connection with said valve element through said aperture for moving said valve element downwardly against the force of said spring to close the upper end of the stand pipe off from said steam space, gasket means sealing said dome against the escape of steam through said aperture, and means providing a passageway from the water space into said stand pipe, said last means comprising a duct having one end located in the water space in the reservoir at a point near the bottom of the reservoir, the other end of said duct communicating with said stand pipe.

at a point below its upper end and said valve element.

8. A steam iron as in claim 7, wherein said operating member is loose from said valve element and normally in loose abutting relation thereto through said aperture.

9. A steam iron as in claim 7, wherein said operating member is loose from said valve element and normally in loose abutting relation thereto through said aperture, a support for said member, means releasably latching said support to said reservoir, said support when unlatched and moved away from said reservoir carrying

8
said member out of abutting relation to said valve element.
